CATHODE RAY TUBE AND LIGHT BEAM
CONTROL MEANS

Robert Eugene Ricketts, Plainfield, N. J.

Application July 24, 1942, Serial No. 452,221

7 Claims. (Cl. 178—7.5)

This invention relates generally to the class of electronics and pertains particularly to improvements in cathode ray tubes together with a novel and improved means of controlling the operation thereof.

A principal object of the present invention is to provide a cathode-ray tube designed in such a manner as to provide a low voltage operating tube having a very high degree of sensitivity.

Another object of the invention is to provide an improved cathode-ray tube having, in addition to an electron generating or producing source, a source of secondary emission electrons which are produced by the bombardment of an electron emitting element by the primary or initially produced electrons and which are condensed with the primary electrons into the spot or trace producing ray which is directed against the fluorescent screen and is caused to move thereacross in the customary manner.

Still another object of the invention is to provide an improved cathode-ray tube having as the cathode for the production of the primary electron streams, a light sensitive electron emitting screen or wall in an end of the tube which is activated by the application thereto of a pencil or beam of light.

Still another object of the invention is to provide an improved cathode-ray tube having the light sensitive electron emitting screen forming the cathode, with a novel means for controlling or varying the intensity of a light beam applied thereto, in accordance with or in response to received signals or signal impulses, whereby to obtain the desired variations in intensity of the electron beam falling upon the fluorescent screen within the tube.

Still another object of the invention is to provide in association with an improved cathode-ray tube of the character stated, an improved light beam intensity controlling cell operating upon the principle of the well known Kerr cell, in response to variations in received signals.

The invention will be best understood from a consideration of the following detailed description taken in connection with the accompanying drawing, it being understood, however, that the invention is not to be considered as limited by the specific illustration or description but that such illustration and description constitute a preferred embodiment of the invention.

In the drawing:

Figure 1 is a view illustrating the light beam control means, and a portion of the tube.

Figure 1^a is a diagrammatic longitudinal section of the tube.

Figure 2 is a fragmentary detail showing a modified embodiment of the cathode screen.

5 Referring now more particularly to the drawing the reference character E generally designates the envelope of the present cathode-ray tube. This envelope may be formed of glass, metal or other suitable material in accordance with practice. This tube may be of any suitable design but is here illustrated as of conventional design in having the relatively long straight portion 10 having the closed end wall 11 and merging at its other end in the flared or conical portion 12 which is closed by the rounded front or convex wall 13. Upon the inner face of the wall 13 is applied a coating or layer of a suitable fluorescent material 14.

20 In accordance with one embodiment of the present invention the rear end wall 11 of the envelope is covered upon its inner side with a layer or coating 15 of any suitable light sensitive material such as, for example, some alkaline metal like potassium or rubidium which emits electrons 25 when acted upon by light.

Suitably spaced from the electron emitting coating or electrode 15 is the first anode 16 and disposed adjacent this anode but electrically spaced therefrom, at the end of the anode nearest 30 the cathode 15 is the grid screen 17. This grid screen may be placed to encircle the end of the first anode nearest the cathode as illustrated but is, as previously stated, in spaced relation therewith.

35 The first anode 16 is in the form of a tube or sleeve and encloses a series of diaphragms 18 each of which has an opening 19 therethrough. These openings are aligned in a path oblique to the axial center of the anode for the purpose of 40 condensing the electron stream entering from the cathode, to flow out of the forward end of the first anode at an angle or oblique to the axial center of the envelope for the purpose herein-after stated.

45 Completing the electron gun is the second anode 20 which is located in the customary manner in advance of the first anode and which is of tubular or sleeve like form and has within it 50 the diaphragms 21 each of which has a central opening 22 for the passage of the electron stream. The apertures 22 are aligned upon the axial center of the envelope and of the second anode so that the electron stream when flowing to the 55 fluorescent screen without being acted upon by

the deflection elements, will travel along the axial center of the envelope.

Interposed between the first and second anodes is an electron multiplier unit which is indicated generally by the numeral 23. This unit 23 is made up of a number, preferably four, of electrically separated plates 25 which are of arcuate cross-section. These plates are assembled, as illustrated, to form a tube which is coaxial with the envelope and with the first and second anodes.

The plates 25 of the electron multiplier unit 23 are of a metal having a low work function which when bombarded or struck by electrons moving at high velocity, will emit electrons. The first electrode is constructed and arranged so that the electron stream passing therethrough will be directed at an angle against the inner surfaces of the plate of the multiplier unit so as to create a secondary electron emission in this unit. If such a unit were in the form of a single tube the electrons impinging against the inner surface thereof and those electrons caused to be emitted by such impingement would follow a sinusoidal path. By forming such a tubular unit into sections as illustrated and by applying electric potential to the separate sections or plates, the electrons will, instead of describing one revolution, travel through many revolutions within the unit and by impingement a large number of times against the inner surfaces of the plates before leaving the unit, cause the emission of large numbers of secondary electrons which will enter the stream passing on from the multiplier unit to the second anode.

Any suitable means may be employed for applying potentials to the plates 25 of the electron multiplier unit, one means being here shown as in the form of a number of series connected sources of potential 28 each of which is connected by a pair of conductors 27 across two oppositely positioned plates 25.

The inner surface of the envelope is covered by a suitable metallic current conducting coating 28 which extends from a position adjacent to the cathode 15 to the opposite end of the envelope where it terminates short of the fluorescent screen 14. This coating functions in the customary manner to drain off electrons from the fluorescent screen and is electrically connected with the grid screen 17 in the arrangement shown when the grid screen is not employed to control the intensity of the electron stream under the action of the modulated current signals received, when the tube is employed in receiving television signals. When this grid screen is made use of for controlling the intensity of the electron stream, the conducting coating 28 may be connected with the second anode as is customary, the grid screen 17 then being hooked up with the signal receiving circuit to retard or accelerate the electrons emitted from the cathode, in response to signal variations.

The elements of the electron gun are here illustrated as being connected with a conventional voltage divider 29 whereby the desired potentials may be applied to the cathode, grid screen and anodes.

Deflection of the electron beam, designated B, to effect the desired movement of the spot 29' may be accomplished by the employment of the magnet coils 30 or by the use of the well known deflection plates, not shown.

While there has been illustrated in association with the electron multiplier unit 23, a cathode

consisting of a light sensitive material coating at the inner end of the tube, the multiplier unit may be employed, if desired, with a regular or standard hot filament cathode for generating the electron stream or beam.

The invention also contemplates the employment of a screen 30' of suitable translucent or transparent construction and carrying or impregnated with suitable light sensitive chemicals, in place of the light sensitive coating forming the cathode 15. This screen cathode as well as the coating 15 may be flat or concave as desired. The latter formation is preferred, however since this formation facilitates the focusing of the emitted electrons toward the center of the grid screen and into the adjacent end of the first anode.

The numeral 31 designates a light source for the production of a light beam 32 directed against the light sensitive electrode 15 or 30'. This light beam 32 is preferably, though not necessarily, passed through a condensing lens 33, and then a polarizer 34 such as a Nicol prism, to a second Nicol prism 35 which functions in the well known manner as an analyzer for the plane-polarized light beam issuing from the first prism.

Interposed between the prisms 34 and 35 is a light beam rotating unit which is indicated generally by the numeral 36 and by means of which the intensity of the light beam 32 can be diminished or caused to increase to its maximum before striking the electron producing cathode in the end of the envelope.

A second lens 37 may, if desired, be interposed between the analyzer prism and the cathode of the tube or envelope.

The light beam rotating unit 36 is of novel design in that it comprises four spaced parallel transversely arcuate plates 38 which are grouped about and parallel the light beam, which beam passes along the center of the space between the grouped plates.

The plates of the light beam rotating unit are coupled as illustrated, through the medium of the transformer unit 39 with the signal receiving system to receive the incoming signals. As a result the electrostatic field between the plates 38 is constantly varied in intensity in accordance with variations in the received signals, to thereby rotate the plane-polarized light beam so that more or less thereof may pass through the analyzer prism 35. The light beam density controlling unit or rotating unit 36 in effect consists of two Kerr cells placed parallel with the ray or beam of light, one being disposed vertically and the other horizontally. One cell deflects the light and varies it vertically on its axis, as to intensity while the other cell affects the light beam horizontally, the two cells working together in the manner previously described to control the intensity of the beam. As shown two opposite plates are hooked up in one circuit and the other two opposite plates are hooked up in another circuit or, if desired, they may be hooked up in parallel.

In place of the light beam rotating unit 36 or Kerr type cell there may be used in this system, if desired, a supersonic light valve.

In the multiplier unit 23 a number of different metals may be employed for the production of the desired secondary emission of electrons. As an example, there may be employed silver or platinum, silver having a coating of caesium or platinum coated with caesiated silver, caesium having a coating of caesium oxide, barium having a coating of barium oxide, barium oxide on silver and

silver plated platinum. In general, caesium coated metallic plastes or bodies will function as desired, using metals having a low work function. Rubidium having a coating of rubidium oxide, or silver on platinum with a rubidium or other alkali metal oxide may also be employed.

Metals having a low work function will produce the desired secondary emission when stretched or placed under tension and such stretching or tensioning may be given to the above stated metals. Parkarized steel with applications of the above stated metallic oxides may also be employed.

It is to be understood that the envelope E of the present invention may be filled or charged with a suitable gas which would aid in the development of the desired secondary emission.

From the foregoing it will be readily apparent that the present invention comprises an entirely new and novel type of cathode-ray tube by means of which all of the functions normally carried out by a vacuum tube of this character may be readily accomplished with a lower current consumption and without sacrificing desirable features. With this improved cathode-ray tube a larger electron emission is obtained under low current voltage, with a considerably greater sensitivity, than is possible with tubes not having provision for secondary electron emission.

It will also be apparent that a new and novel arrangement is disclosed for controlling the lumen intensity of the light pencil employed for exciting the light sensitive electron emitting substance upon the rear end of the tube.

Reference has been made to the use of "Parkarized" steel as a suitable material to be used in the electron amplifier, either alone or as a support for other electron emitting substances. This steel is prepared, broadly, by treating the metal, by dipping or in any other manner, with acids and then with alkalies which tends to make the surface of the metal somewhat rough and porous. Hence, the surface of such metal may be a good emitting surface under certain conditions.

I claim:

1. A cathode ray-tube including a source of primary electrons, a first anode adjacent said source and a second anode, means for generating secondary electron emission comprising a cylindrical unit interposed between the first and second anodes and arranged to have the electron beam from the primary source directed therein to and against the inner wall thereof, said unit consisting of metal having the capacity to emit electrons under electronic bombardment, said cylindrical unit being longitudinally divided to form a number of spaced parallel plates, and means for applying an electrical potential to said plates to set up an electrostatic field therebetween.

2. In a cathode-ray tube, a primary source of electron emission at one end of the tube, a first anode disposed in advance of said source, a grid screen adjacent said anode for directing the electron flow from the source to the center of the first anode, a second anode spaced from the first anode, said first anode being constructed and arranged to focus the electron stream toward the

second anode along a path oblique to the axial centers of the anodes, a tubular secondary electron emitting unit disposed coaxially with and between the first and second anodes and spaced therefrom, the focusing anode functioning to direct the electron stream into and against the inner wall of said unit, and means for establishing an electrostatic field within said unit.

3. In a cathode-ray tube, a primary source of electron emission at one end of the tube, a first anode disposed in advance of said source, a grid screen adjacent said anode for directing the electron flow from the source to the center of the first anode, a second anode spaced from the first anode, said first anode being constructed and arranged to focus the electron stream toward the second anode along a path oblique to the axial centers of the anodes, a tubular secondary electron emitting unit disposed coaxially with and between the first and second anodes and spaced therefrom, the focusing anode functioning to direct the electron stream into and against the inner wall of said unit, means for establishing an electrostatic field within said unit, said source of primary electrons comprising a screen of light sensitive electron emitting material.

4. A cathode-ray tube structure as set forth in claim 2 in which said source of primary electrons comprises a screen of light sensitive electron emitting material, and means for applying a negative potential to said screen and gradually increasing positive potentials respectively to the grid screen and first and second anodes.

5. A cathode-ray tube structure as set forth in claim 2 in which said tubular unit comprises a series of longitudinal spaced parallel plates disposed in electrically separated relation, means for applying electric potentials of opposite polarity to opposite plates of said unit, and means for applying a negative potential to said light sensitive screen and progressively positively increasing potentials respectively to the grid screen and first and second anodes.

6. An electro-optical system comprising an evacuated tube having a fluorescent screen at one end, a screen of light sensitive electron emitting material in the opposite end of the tube designed to emit electrons under the action of light falling thereon, spaced first and second anodes within the tube and aligned between said screens, an electron stream deflecting means, said second screen when subjected to a light beam emitting electrons, said anodes being arranged to receive and focus said electrons onto the first screen, a light source disposed in position to project a light beam on the second screen, a pair of Nicol prisms interposed between the light source and the second screen, and means interposed between the Nicol prisms for axially turning the light beam in response to changing electrical signal impulses to control the intensity of the light beam falling upon said second screen.

7. A system as set forth in claim 6 in which said last means comprises two pairs of electrically separated plates disposed around and parallel with the light beam and means for applying electric potentials of opposite polarity to the opposite plates of each pair.

ROBERT EUGENE RICKETTS.
